WINDER

Burt A. Peterson, Rockford, Ill., assignor to
 Barber Colman Company, Rockford, Ill., a corporation of Illinois

Application July 7, 1938, Serial No. 217,880

14 Claims. (Cl. 28—68)

The invention pertains to winding machines known as "spoolers," for winding yarn from bobbins onto spools or yarn carriers to form yarn masses or "cheeses"; and has particular reference to the uniform adjustment of the yarn cleaning or clearing devices of the spooler, through which the strands of yarn pass in traveling from the bobbins to the cheeses.

Yarn clearing devices as commonly constructed provide openings for the passage of the yarn, and are made adjustable so that the size of the openings can be changed in accordance with variations in the size or gauge of the yarn being spooled. In some mills the size of the yarn being spooled is changed frequently and it is therefore necessary to make frequent adjustments of the clearing devices. The practice heretofore employed in making such adjustments has been to adjust the size of the opening in each of the clearing devices by the use of a feeler gauge in the opening to determine the extent of movement to be imparted to the adjusting screw or other means provided for that purpose. The accurate adjustment of the clearing devices requires the exercise of great care, and where a large number of devices are to be adjusted a substantial amount of time is consumed during which the machine must be idle.

With the foregoing in view, the primary object of the present invention is to provide for the adjustment of the clearing devices of a spooler rapidly and uniformly in order to facilitate and expedite changes in the size of the yarn being spooled.

Another object is to provide for the uniform adjustment of a plurality of clearing devices by means operative to afford a positive indication to the operator when each of the devices has been adjusted to a predetermined setting.

A further object is to provide an adjustable setting device adapted for use in adjusting a plurality of yarn clearers uniformly and expeditiously.

Another object is to provide in a yarn clearing device, means of an advantageous character for adjusting the size of the opening through which the yarn passes in traveling from the bobbins to the cheeses.

In the accompanying drawings,

Figure 1 is a fragmentary elevational view partially schematic in character and showing a plurality of clearing devices in their relation to a series of bobbins and a series of cheeses in the operation of the spooler.

Fig. 2 is an end view of one of the clearing devices.

Fig. 3 is a fragmentary front elevational view of a clearing device with parts broken away to show the adjusting means.

Fig. 4 is a sectional view of a yarn clearing device taken approximately in the plane of line 4—4 of Fig. 3, and showing in addition a manually operable setting device forming part of the means for setting the yarn clearer to provide openings of varying sizes for the passage of the yarn, said setting device being shown in section and its position when in operative relation to the yarn clearer being shown in broken lines.

Fig. 5 is an end view of the manually operable device.

Fig. 6 is a front view and Fig. 7 an end view of a modified form of clearing device.

Fig. 8 is a sectional view taken approximately in the plane of line 8—8 of Fig. 6, the manually operable device of the setting means being shown in broken lines.

Referring first to Fig. 1 of the drawings, a plurality of clearing devices 9 are shown in operative relation to strands of yarn *a* passing from bobbins 10 to cheeses 11 in peripheral contact with a driving drum 12. The clearing devices are mounted upon bobbin pockets 13 directly above the bobbins. Except for the adjusting means, the clearing devices shown in Figs. 2 to 4 are of the construction disclosed in the patent to Peterson No. 1,663,856, dated March 27, 1928.

Generally stated, each of the clearing devices 9 comprises a pair of blades 14 carried by spaced parallel rock shafts 15 and disposed in V-shaped relation with the free edges of the blades held in spaced parallel relation to form an opening 16 (Fig. 2) for the passage of the yarn strand *a*. The shafts 15 are mounted in a suitable U-shaped frame 17 also carrying parallel rods 18 for guiding the yarn. The frame 17 provides two upright parallel standards 19 (Fig. 3) in which the rods 18 and the rock shafts 15 are mounted.

The size of the opening 16 formed between the blades 14 of each clearing device must be adjusted in accordance with the size of the yarn to be spooled. Such adjustment is accomplished by means of an adjusting element preferably in the form of a cam 20 acting upon a follower, which in this instance is a plate or slide 21.

In the embodiment shown in Figs. 2 to 4, the cam follower slide 21 engages with a spreader bar 22 interposed between and acting upon the blades 14. As herein shown, the bar 22 has one end anchored in one of the standards 19 and

the other end projecting through an elongated opening in the other standard into position between the blades at inner ends thereof, as shown in Fig. 3.

5 The cam is arranged for angular movement by means of a rotatably mounted stud 23, and the follower slide 21 is held in engagement with the cam by means of a spring 24 acting upon the spreader bar 22 which in turn bears upon 10 a depending portion 25 of the slide 21. The cam 20 and the parts immediately associated therewith may be supported in the frame 17 by any suitable or preferred means.

In the present instance the cam is disposed 15 within an opening 26 in the slide 21 and bears against an inward projection 26a at the lower side of the opening. The cam is suitably fixed to the stud 23 as by being pinned to a collar 27 rigid with the stud forwardly of the slide.

20 The stud is rotatably mounted in a bearing sleeve 28 carried by the upper one of two frame plates 29 which are interposed between the vertically spaced guide rods 18, the plates being suitably grooved at their top and bottom edges 25 to conform with the circular contour of the rods. At its rear end the stud is threaded to receive clamping nuts 30 acting upon a spring washer 31 and a flat disk 32, the latter encircling the bearing sleeve and bearing against the rear side 30 of the rods 18. Forwardly of the slide is a cover plate 33 interposed between the standards 19 of the frame 17 (Fig. 3) and apertured to receive the collar 27 on the stud, the collar being formed with a flange 34 bearing against the front face 35 of the cover plate. If desired, the space between the lower pair of rods 18 may be closed by a plate 35 similar to the plate 29.

For the purpose of making like adjustments 40 of the clearing devices of a spooler, the present invention provides a setting means comprising the adjusting stud 23 and an adjustable setting device 36 with coacting stops on the setting device and the cover plate 33 of each of the clearing devices.

45 In the present instance the device 36 is in the form of a separate implement adjustable in accordance with variations in the size of the yarn to be spooled and adapted to be applied to the adjusting studs 23 of the various clearing 50 devices. As shown it comprises a shank 37 equipped with a suitable handle 38 and carrying a head 39 providing an irregular socket 40 for coaction with the stud 23. In the present instance the socket is of cylindrical contour except 55 for a flat side 41 (Fig. 5), and is adapted to fit over an enlarged forward end portion 42 of the stud 23 which is complementary in shape to the socket 40.

The socket 40 of the setting device is formed 60 in a sleeve-like member 44 fitting within the head 39, the parts being adapted to be secured in various angular relations by means of a set screw 45. The head 39 also carries a spring pressed plunger 46 adapted for coaction with a 65 hole 47 in the cover plate 33 when the parts are in the relation shown in broken lines in Fig. 4.

It will be seen that due to the irregular shape 70 of the socket 40 and of the stud portion 42, the setting device 36 can be applied to the adjustment of a clearing device in only one predetermined angular relation of the socket member 44 and the stud 23. Also it will be seen that the plunger 46 of the setting device and the hole 47 in the cover plate constitute coacting stops 75 positively determining the extent of angular mo-

tion imparted to the cam 20 by the operation of the setting device, and for any given position of the stop or plunger 46 relative to the socket member 44 in the head 39, the cam 20 of any of the clearing devices may be adjusted to change the size of the opening 16 corresponding to the adjustment of the setting device. All that is necessary, therefore, is to set the socket in the setting device according to the size of the desired opening 16 in the clearing device, and then turn the adjusting studs of the various clearing devices until the coacting stops 46 and 47 interengage, whereupon the blades 14 of each of the clearing devices will be adjusted to the same size of opening. To facilitate the relative adjustment of the plunger stop 46 and the socket member 44 for any given size of yarn, the face of the head 39 may be provided with a suitable dial 48 (Fig. 5) and the face of the socket may be provided with a coacting index point 49.

The use of cam means for adjusting the clearing devices is advantageous in that it renders it possible to obtain uniformly graduated variations in the size of the opening 16 of any clearing device for a corresponding angular motion of 25 the operating stud 23. In each instance, the maximum range of adjustment of the opening is obtained by an angular movement of the stud and therefore of the cam 20 through 360°, and as shown in Fig. 5, the graduations of the scale 30 or dial 48 are spaced apart uniformly. Also by properly shaping the cam it is possible to compensate for variations in the movements imparted to the blades 14 incident to the angular relation of the surfaces of the blades engaged by the spreader bar 22, it being observed that movements of uniform length imparted to the spreader bar would not effect corresponding uniform changes in the size of the opening between the blades.

In Figs. 6 to 8, the invention is shown applied to a modified form of clearing device comprising a single blade 51 mounted upon a rock shaft 52 and movable therewith relative to a stationary thread guiding surface formed on a plate 53 to 45 vary the size of the opening 16' (Fig. 7) for the passage of the yarn. A coiled spring 54 surrounding the shaft 52 exerts a rotative force thereon in a direction to carry a transverse pin 55 into engagement with the lower end of a slide 21' 50 operable by means which in all material respects is like that described in Figs. 2 to 4. In this particular embodiment, the cover plate is in the form of a disk 56 having a depending arm 57 engaging in a slot 58 in a flange 59 projecting from 55 the plate 53. Also the rear clamping disk 29' has a depending portion 32' slotted at 61 to receive a projecting portion of the pin 55 which acts to hold the shaft 52 against endwise movement.

It will be observed that the present invention provides for the uniform adjustment of a plurality of clearing devices in a spooler in a manner such as to simplify and expedite greatly the operation of changing the size of the yarn 65 being spooled. With one adjustment of the setting device according to the size of the yarn to be spooled, as indicated by the dial on the face of the head 39, it is only necessary to turn the adjusting studs 23 of each of the clearing devices 70 until the coacting stops 46 and 47 interengage. Such interengagement of the stops affords a positive indication to the operator that the opening provided for the passage of the yarn has been adjusted to the proper size for the yarn 75

which is to be spooled. Accordingly, it is unnecessary for the operator to make any accurate measurements or observations or to exercise any particular care in performing the adjusting operations.

5. I claim as my invention:

1. The combination of a yarn clearing device having means defining an opening for the passage of a strand of yarn, means operable to change the size of said opening including an adjusting element, and means for setting said element comprising a rotary shaft, a stationary part providing a stop, a member arranged for disengageable connection with said shaft in one predetermined angular relation only of the member relative to the shaft, a second member carrying a second stop, and means for adjustably securing said members together in different angular relations, said second stop being adapted to engage with the stop associated with the shaft to determine the extent of angular movement imparted to the shaft.

2. The combination of a yarn clearing device having means defining an opening for the passage of a strand of yarn, means operable to change the size of said opening including an adjustable element, and means for setting said element comprising a rotary member, a stationary part providing a stop, and a manually operable member interengageable with said rotary member in one predetermined angular relation only of said members, said manually operable member having associated therewith a part carrying a second stop and relatively adjustable to vary the angular relation of the stop relative to the member, said two stops being adapted to interengage to determine the size of said opening, and one of said stops having a spring urging it into engagement with the other stop as an incident to relative rotation between said members.

3. The combination of a yarn clearing device having means defining an opening for the passage of a strand of yarn, means operable to change the size of said opening including an adjusting element, and means for setting said element comprising a stationary member providing a stop and a manually operable member for moving said element having associated therewith a second stop, one of said stops being adjustable relative to its associated member, and said two stops being adapted to interengage to determine the size of said opening.

4. The combination of a yarn clearer having means defining an opening for the passage of a strand of yarn, means operable to change the size of said opening including an adjusting element, and means for setting said element comprising a stationary part providing a stop and a manually movable part having a stop, said manually movable part and its stop being adjustable relative to each other to vary the setting of said element when said stops are in interengaging relation.

5. The combination of a yarn clearing device having means defining an opening for the passage of a strand of yarn, means operable to change the size of opening including an adjusting element, and means for setting said element comprising a stationary part providing a stop, and a manually operable member having a disengageable connection with said element to move it and adapted to cooperate with said stop to set said element in a predetermined position.

6. The combination of a yarn clearer having

means defining an opening for the passage of a strand of yarn, means operable to change the size of said opening including an adjusting element, and operating means comprising relatively movable parts respectively having stops 5 coacting to determine the setting of said element, one of said parts and its associated stop being relatively adjustable to vary the setting of said element when said stops are in interengaging relation.

7. The combination of a yarn clearer having means defining an opening for the passage of a strand of yarn, means operable to change the size of said opening including an adjusting element, and operating means comprising relatively 15 movable parts having stop means coacting to determine the setting of said element, said stop means being relatively adjustable.

8. A setting device for a plurality of yarn clearers each having a rotatable adjusting element and an associated stop, said device comprising a member arranged for association with said element in one predetermined angular relation only and operable to turn said element relative to its stop, a second member encircling the 20 first member and carrying a second stop, and means for adjustably securing said members together in different angular relation, said second stop being adapted to interengage with the stop associated with said element to determine 25 the extent of angular movement imparted thereto.

9. A setting device for a plurality of yarn clearers each having a rotatable adjusting element, said device comprising a member arranged for association with said element in one predetermined angular relation only and operable to turn 30 said element, a second member, and means for adjustably securing said members together in different angular relations.

10. The combination of a spooler having a plurality of yarn clearing devices each having means defining an opening for the passage of a strand of yarn and an adjusting element for changing the size of said opening, and means 45 common to and operative independently upon the several devices to impart uniform adjusting movements to the elements thereof, each of said devices having a part cooperating with the last mentioned means to determine the extent of 50 adjusting movement imparted thereto.

11. The combination of a yarn clearer having means defining an opening for the passage of a strand of yarn, cam means operable to change the size of said opening including a rotary shaft, 55 and means for turning said shaft into any one of a plurality of positions comprising a setting device having a part engageable with said shaft in one angular position only relative thereto and an operating member angularly adjustable relative to said part, and means cooperating with said member to limit the rotational movement imparted to the shaft by said device.

12. A clearing device comprising, in combination, means defining a stationary yarn guiding 65 surface, a rock shaft parallel to said surface, a blade carried by said rock shaft and coacting with said surface to form an opening for the passage of a strand of yarn, a rotatable support, and means operable on said rock shaft in the rotation of said support to shift the position of said blade relative to said surface.

13. The combination of a yarn clearing device comprising a stationary support, means on said support for defining an opening for the passage 75

of a strand of yarn including an element movable to vary the size of said opening, a shaft journalized in said support, a cam on said shaft, and a slide mounted on said support and operable by said cam into engagement with said movable element; and a device removably associated with said shaft to impart angular movement thereto, said support having means cooperating with said device to determine the extent of said angular movement.

14. The combination of a spooler having a

plurality of yarn clearing devices each having means defining an opening for the passage of a strand of yarn and an adjusting element for changing the size of said opening, means for imparting angular adjusting movements to said elements, and means cooperating with the last mentioned means for determining the extent of angular movement imparted to said elements whereby to effect a predetermined change in the size of each of the devices.
